ELECTRIC MOTOR REVERSING CONTROL

Jack E. Reilly, Wilkinsburg, Pa., assignor to Westinghouse Electric Corporation, East Pittsburgh, Pa., a corporation of Pennsylvania

Application June 16, 1945, Serial No. 599,839

7 Claims. (Cl. 318—261)

1

This invention relates to electrical systems and, in particular, to control systems for reversible motors of the type utilized in arc furnace regulating systems.

In electronic arc furnace regulating systems, a motor is employed for positioning an electrode, the speed and direction of operation of which is controlled by two sets of electric valves, the biases of which are controlled by a pair of control valves operative in response to the arc potential and the current flowing through the electrode. Thus, the operation of the system is primarily controlled by the operation of the control valves, and if one of the control valves should fail, the system fails to operate in the manner for which it is designed. In particular, if the control valve which controls the operation of the motor to lower the electrode should fail, considerable damage to the furnace and to the system may occur.

An object of this invention is to provide in an electronic arc furnace regulating system for automatically providing protection for the system where failure of the control valve controlling the lowering of the furnace electrode is encountered.

Another object of this invention is to provide an electronic control system for a reversible motor in which operation of the motor in one direction is prevented upon failure of the control valve which normally controls the operation in the one direction.

A more specific object of this invention is to provide an electronic arc furnace regulating system for automatically preventing the lowering of an electrode when the control valve controlling such operation fails.

Other objects of this invention will become apparent from the following description when taken in conjunction with the accompanying drawing, the single figure of which is a diagrammatic view of the apparatus and circuits of an arc furnace regulating system embodying the teachings of this invention.

Referring to the drawing, this invention is illustrated by reference to an arc furnace 10 having electrodes 12, 14 and 16 disposed therein to be positioned with respect to a metal charge 18. The electrodes 12, 14 and 16 are connected by conductors 20, 22 and 24, respectively, to a source of supply (not shown). Since the control system and apparatus for each of the electrodes is the same, only the system and apparatus associated with electrode 14 is illustrated, it being understood that similar control systems are to be provided for the other electrodes.

2

As illustrated, a reversible motor 26 is utilized for positioning the electrode 14, the electrode 14 being connected to be raised or lowered by operation of the motor. For this purpose, a winding drum 28 is disposed to be driven by the motor 26, a flexible cable 30 being connected to the electrode 14 and disposed to be wound upon the drum 28. The motor comprises an armature winding 32 and a field winding 34, the field winding being disposed to be separately excited from a source of supply (not shown).

In order to control the direction and speed of operation of the motor 26, two sets of gas filled electric valves, such as the thyratron valves 36—38 and 40—42 are utilized. The valves 36, 38, 40 and 42 are provided with anodes 44, 46, 48 and 50, respectively, connected to the terminals of the secondary windings of transformers 52 and 54 as illustrated, the primary 15 windings of the transformers being connected across supply conductors 56 and 58. The valves 36, 38, 40 and 42 are also provided with cathodes 60, 62, 64 and 66, respectively, the cathodes 60 and 62 being connected through conductors 68—70 and 72, respectively, conductors 74 and 76, resistor 78, armature windings 32, resistor 80, conductor 82, contact member 84 of a contactor 86, and conductor 88 to the center tap of the secondary winding of transformer 52. In a 20 similar manner, the cathodes 40 and 42 are connected by conductors 90 and 92—94, respectively, through conductors 96 and 98, resistor 100, armature windings 32, resistor 102, conductor 104, contact member 106 of a contactor 108, and conductor 110 to the center tap of the secondary 25 winding of transformer 54.

The valves 36, 38, 40 and 42 are also provided with grids 112, 114, 116 and 118, respectively. The grids 112 and 114 are supplied with an alternating current potential from the supply conductors 56 and 58 through a transformer 120, a phase shifting circuit 122 and a grid transformer 124. The secondary winding of the grid transformer comprises two sections 126 and 128, the 30 winding 126 having one end connected through a resistor 130 to the grid 114 and the other end connected through a conductor 132, a part of resistor 134, and the conductor 72 to the cathode 62 of valve 38 whereas the winding 128 has one 35 end connected through resistor 136 to the grid 112 and the other end connected through conductor 138, resistor 140, and conductors 74, 70 and 68 to the cathode 60 of the valve 36.

Alternating-current potential is also supplied 40 to the grids 116 and 118 of valves 40 and 42, re-

spectively, from supply conductors 56 and 58 through transformer 142, the phase shifting circuit 144 and the grid transformer 146 which is provided with two secondary windings 143 and 150. The winding 143 has one end connected through resistor 152 to the grid 118 of valve 42, the other end of winding 143 being connected through conductor 154, resistor 156, and conductors 96, 98 and 92 to the cathode 66. The secondary winding 150 has one end connected through resistor 158 to the grid 116 of valve 40 and the other end is connected through conductor 160, a part of resistor 162 and conductor 90 to the cathode 64.

Potentiometer resistors 164 and 166 are disposed in circuit relation with the grids 112—114 and 116—118, respectively, of the valves 36—38 and 40—42, respectively, for controlling the grid-cathode potential of the valves in a predetermined manner. Thus one end of the resistor 164 is connected through conductors 68 and 70—72 to the cathodes 60 and 62, respectively, and a flexible lead 168 connected to an intermediate tap or resistor 164, is connected through resistor 170, conductor 172, resistor 174, and conductor 138 to the secondary winding 123, the conductor 172 also being connected through a part of resistor 134 and conductor 132 to the secondary winding 126 of the grid transformer 124. In the same manner one end of resistor 166 is connected through conductors 92 and 94—96 to the cathodes 118 and 116, respectively, of valves 42 and 40, respectively, and a flexible lead 176 connected to an intermediate tap of the resistor 166, is connected through resistor 178, conductor 180, resistor 182, and conductor 154 to the secondary winding 148, the conductor 180 also being connected through a part of resistor 162 and conductor 160 to the secondary winding 150 of the grid transformer 146.

In order to control the direct-current biasing potential for the electric valves 36—38 and 40—42, vacuum type discharge valves 184 and 186, respectively, are provided being disposed to normally control the current flow through the potentiometer resistors 164 and 166, respectively. In addition to the valves 184 and 186, a master controller 188 and a single phase controller 190 are also provided for manual control of the system to effect a raising or lowering of the electrode 14 and a switching contactor 192 is provided for automatically controlling the bias of the valves 36 and 38 in case the control valve 184 fails.

Only one part of the master controller 188 is illustrated as having segments 194, 196, 198, 200 and 202, it being understood that in practice the master controller is provided with three sets of such segments, one set for each phase, whereby simultaneous adjustment may be obtained in the control system of each phase. The single phase controller 190 shown in the "off" position is of the well known type having "lower," "off" and "raise" positions and having segments 204, 206, 208, 210, 212 and 214 positioned to engage co-operating pairs of contact fingers in certain of the positions to establish different circuits.

The control valves 184 and 186 are provided with anodes 216 and 218, respectively, grids 220 and 222, respectively, and cathodes 224 and 226, respectively. The anodes 216 and 218 are connected by conductors 228 and 230, respectively, to an output terminal of associated rectifier bridges 232 and 234, respectively, which are supplied from transformers 236 and 238, respectively,

the primary windings of the transformers being connected across supply conductors 56 and 58.

The cathode 224 of control valve 184 is normally connected through a self-biasing resistor 240, a flexible lead 242 connected to an intermediate tap of a resistor 244, conductor 194, resistors 102 and 198, conductors 76, 74 and 70, potentiometer resistor 164, conductor 246, segment 200 of controller 188, segment 210 of controller 190, conductor 248, and smoothing reactor 250 to the other output terminal of the rectifier 232. In a similar manner, the cathode 226 of control valve 186 is connected through a self-biasing resistor 252, flexible lead 254 connected to an intermediate tap of a resistor 256, conductor 82, resistors 80 and 108, conductors 98, 96 and 94, potentiometer resistor 166, conductor 258, segment 208 of controller 190, segment 198 of controller 188, conductors 260 and 262 and smoothing reactor 264 to the other output terminal of the rectifier 234.

In order to control the biasing potential of the grids 220 and 222 of the control valves 184 and 186, respectively, the grids are so connected that their potentials are controlled in response to the current flowing through the electrode 14 and the arc potential across the electrode arc. Thus, the grid biasing circuit for the valve 184 extends from the grid 220 through a grid resistor 266, conductor 268, series connected resistors 270 and 272, conductor 274, segments 196 and 206 of controllers 188 and 190, respectively, conductors 276 and 76, resistors 78 and 102, conductor 194, part of resistor 244, flexible conductor 242 and the self-biasing resistor 240 to the cathode 224.

The resistors 270 and 272 are control resistors and are disposed to have a direct-current voltage thereacross proportional to the arc potential and to the flow of current through electrode 14, respectively. For this reason, the resistor 270 is connected across a rectifier bridge 278 which is connected through a transformer 280, the terminals of the primary winding of which are connected by conductors 282 and 284 to the supply conductor 22 and to the receptacle of the grounded furnace 10, respectively. The control resistor 272 is also connected across a rectifier 286 which is supplied by a transformer 288 connected to be energized by the current transformer 290 in accordance with the current flowing in conductor 22. The transformers 280 and 288 are preferably of a one to one ratio and are employed primarily to prevent sneak circuits or effects on the grids of control valves 184 and 186.

As illustrated, the rectifier bridges 278 and 286 are connected in opposition whereby the direct-current voltages across resistors 270 and 272 are of opposite polarity. Thus, for any variation in the flow of current through electrode 14 and in the arc potential, the differential of the direct-current voltages across the series connected resistors 270 and 272 normally controls the direct-current biasing potential on the grid 220 of control valve 184.

The grid 222 of control valve 186 is likewise connected through a grid resistor 290, conductor 292, series connected resistors 294 and 296, conductor 298, segments 194 and 204 of controllers 188 and 190, respectively, conductors 300 and 98, resistors 100 and 88, conductor 82, a part of resistor 256, flexible lead 254, and the self-biasing resistor 252 to the cathode 226. The control resistor 294 is connected across rectifier bridge 302 which is connected to be supplied through conductors 282 and 284 in accordance with the arc

potential. The control resistor 296 is also connected across a rectifier bridge 304, the input terminals of which are connected across the current transformer 290 whereby the direct-current voltage impressed across resistor 296 is proportional to the current flowing through the electrode 14. The rectifier bridges 302 and 304 are so connected across the resistors 294 and 296, respectively, that the direct-current voltages impressed thereacross are of opposite polarity for normally controlling the direct-current biasing potential of the grid 222 of control valve 186.

The switching contactor 192 comprises the contact members 306, 308, 310, 312, and 314 which are disposed to be actuated when the windings 316 and 318 of the contactor are energized in a predetermined manner. The winding 318 is connected across a rectifier bridge 320 which is supplied by transformer 288 in accordance with the current flow through the electrode 14. The contact members 306 and 312 are "break" contacts, whereas the contact members 308, 310 and 314 are "make" contacts, the "break" contact members being retained in circuit establishing position until after the "make" contact members are actuated to circuit closing positions to maintain the winding 316 always energized during such a switching operation.

It is to be noted that resistor 256 is connected across the terminals of the armature winding 32 of motor 26 and that a voltage drop appears across resistor 256 which is proportional to the voltage being impressed on the armature windings and that as the polarity of the terminal voltage changes, a corresponding change in polarity of the voltage across resistor 256 is obtained. Thus, the winding 316 of contactor 192 is normally disposed to be energized in accordance with the voltage drop across a section of resistor 256 through the circuit extending from an end of resistor 256 through conductors 76 and 276, contact member 306, winding 316, conductor 322, contact member 312, and flexible lead 254 to an intermediate tap of the resistor 256.

When the motor is operating in a direction to lower the electrode 14, the potential across resistor 256 is of such a polarity as to energize the winding 316 to aid winding 318 to tend to actuate the contact members of contactor 192 in an upward direction. However, such operation is not obtained until the combined forces of both windings 316 and 318 reach a predetermined value, as will be explained more fully hereinafter. On the other hand, if the motor is operating to raise the electrode 14, the potential across resistor 256 is of opposite polarity and windings 316 and 318 are energized in opposition to prevent the actuation of the contactor.

When the windings 316 and 318 cooperate to effect the actuation of the contactor, contact member 314 establishes a circuit extending from conductor 228 through conductor 324, contact member 314, and resistors 326 and 240 to the cathodes 224 of control valve 184 to shunt the control valve from the bias control circuit for valves 36 and 38. At the same time, contact members 310 and 308 are actuated to circuit closing positions and immediately thereafter contact members 312 and 306 are actuated to circuit opening positions, the energizing circuit for the winding 318 then extending from conductor 228 through conductor 324, resistor 328, contact member 308, winding 316, conductor 322, contact member 310, conductors 330 and 246, segments 200 and 210 of controllers 188 and 190, respec-

tively, conductor 248 and the smoothing reactor 250 to the other side of the rectifier bridge 232.

The movement of contact member 314 to shunt the control valve 184 also establishes a circuit extending from one side of the rectifier bridge 232 through conductors 228 and 324, contact member 314, resistor 326, flexible lead or conductor 242, part of resistor 244, conductor 104, resistors 102 and 78, conductors 76, 74 and 70, potentiometer resistor 164, conductor 246, segments 200 and 210 of controllers 188 and 190, respectively, conductor 248, and the reactor 250 to the other side of the rectifier bridge 232 whereby the current flow through potentiometer resistor 164 is such as to insure a large negative bias on the grids of valves 36 and 38 to prevent them from conducting.

The resistors 240 and 252 are selected so as to assure a negative bias on the grids of control valves 184 and 186, respectively, when the electrode 14 is in an ideal balanced operating position and the direct-current voltages across control resistors 270—272 and 294—296, respectively, are so balanced that the differential of the direct-current voltages are substantially zero. The potentiometer resistors 164 and 166 in the circuits with the sets of discharge valves 36—38 and 40—42, respectively, are so adjusted by adjusting the flexible leads 168 and 176, respectively, that the drop across the section of the resistors 164 and 166 in circuit with the grids of the valves 36—38 and 40—42, respectively, gives a sufficient dead zone to prevent simultaneous firing of both sets of the discharge valves.

The resistors 78 and 100 in the motor armature circuits controlled by the firing of valves 36—38 and 40—42, respectively, are also connected in the grid circuits of the control valves 184 and 186, respectively, and function to automatically limit the starting current of the motor to a safe value for the valves 36—38 and 40—42, respectively. In addition to limiting the starting current of the motor 26, the resistors 78 and 100 also function to protect the valves 36—38 and 40—42, respectively, from any overload on the system by so controlling the grid bias of the valves that the current flow to the motor 26 is within the safe current limits of the valves. The description of the functioning of the resistors 78 and 100 in the control system may be had by reference to my copending application Serial No. 599,837, filed June 16, 1945, now Patent No. 2,428,583, issued October 7, 1947, and entitled Control systems, in which the valve protecting system is disclosed and claimed.

The resistors 80 and 256 cooperate to permit normal operation of the motor 26 when the valves 36 and 38 are conducting and to provide automatic braking for the motor when the valves 36 and 38 cease to pass current to the motor. Likewise the resistors 102 and 244 cooperate to permit normal operation of the motor 26 when the valves 40 and 42 are conducting and to provide automatic braking of the motor when the current ceases to flow through the valves 40 and 42 to the motor. The system utilizing the resistors referred to for providing automatic braking of the motor is described and claimed in my copending application Serial No. 599,838, filed June 16, 1945, and entitled Control systems.

In operation, assuming that the system is energized, the electrodes 12, 14 and 16 are positioned with respect to the metal charge 18 in the furnace by a manual or automatic operation, such as by operating the master controller 188 or the sin-

gle phase controller 180 to the "lower" position, in which position the contactor 86 is energized and the contactor 108 is deenergized. With the contactor 86 energized, the motor 26 is connected in circuit with the electric valves 36 and 38 to effect an operation of the motor in a direction to lower the electrode 14. If the master controller 188 is utilized to effect the lowering of the electrodes, the electrodes 12, 14 and 16 are lowered simultaneously, whereas if the individual single phase controller 180 is utilized to effect the lowering of the electrode, the electrodes 12, 14 and 16 are independently lowered to contact the metal charge 18, being immediately thereafter withdrawn by operating the master controller 188 or the single phase controller 180 to the "off" position or to the "raised" position to establish an arc between the electrodes and the metal charge.

On the other hand, if it is desired to automatically lower the electrodes 12, 14 and 16 as soon as the system is energized and conductors 20, 22 and 24 are connected to a source of power supply and controllers 188 and 190 are in the "off" position as shown, a potential exists from the electrode 14 to the metal 18 in the furnace. This potential is at a maximum, and since the electrodes 12, 14 and 16 are not as yet adjusted, there is no current flow. The high value of the arc potential impresses a direct-current voltage across each of the control resistors 270 and 294 and since current is not flowing through the electrode 14, the direct-current voltages across resistors 272 and 296 are of zero value. The direct-current voltage across control resistor 270 places a large negative bias on the grid 220 of control valve 184, whereas the direct-current voltage across resistor 294 places a less negative or more positive bias on the grid 222 of control valve 186.

The bias thus impressed on the grid 222 of control valve 186 is such that the control valve is rendered more conductive with the result that current flows from the negative terminal of rectifier bridge 234 through reactor 264, conductors 262 and 260, segments 198 and 208 of controllers 188 and 190, respectively, conductor 258, potentiometer resistor 166, conductors 94, 96 and 98, resistors 190 and 88, conductor 62, a part of resistor 256, the flexible lead or conductor 254, resistor 252, cathode 226 and anode 218 of the control valve 186, and the conductor 230 to the positive terminal of the rectifier bridge 234. Since the direct-current voltage proportional to the arc potential is at a maximum, the conductivity of the control valve 186 is also at a maximum, and maximum current flows through the potentiometer resistor 166. The flow of current through resistor 166 renders the direct-current biasing potential on the grids 116 and 118 of electric valves 40 and 42, respectively, more negative, whereby the grid-cathode potential of the valves is lowered and maintained at a potential below the critical potential of the valves, and the valves 40 and 42 are blocked with the result that no current flows therethrough to the motor 26.

At the same time the large direct-current voltage proportional to the arc potential impressed across control resistor 270 cooperates with the self-biasing resistor 240 to impress a more negative biasing potential on the grid 220 of control valve 184 to decrease the conductivity of the valve 184. Thus, the current flow through potentiometer resistor 164 in the anode-cathode circuit of valve 184 is so decreased that the direct-current biasing potential for the valves 36 and 38

is so reduced that the resultant grid-cathode potential of valves 36 and 38 rises above the critical potential of the valves, and they become highly conductive to pass current to the motor 26. This conducting circuit extends from the center tap of the secondary winding of transformer 52 through conductor 88, contact member 84 of contactor 86, conductor 82, resistor 80, armature windings 32 of the motor 26, resistor 78, and conductors 76 and 74, the parallel conductors 70-68 and 72 to cathodes 60 and 62, respectively, of valves 36 and 38, respectively, anodes 44 and 46, respectively, of the valves 36 and 38, and from thence to the terminals of the secondary winding of the transformer 52 to so energize the motor 26 as to effect the operation thereof in a direction to lower the electrode 14. Since electrodes 12 and 16 are as yet not in contact with the metal 18, the electrode 14 is lowered to a position where it engages the metal charge 18.

As the electrode 14 is lowered, the potential between the electrode 14 and the metal charge 18 decreases with the result that the direct-current voltage across resistors 270 and 294 is so decreased that the bias on the grids of valves 184 and 186 is rendered less negative and more negative, respectively. By rendering the biasing potential of the grid of valve 186 more negative, the current flowing through the potentiometer resistor 166 for controlling the biasing potential of the valves 40 and 42 more nearly approaches the value where the discharge devices 40 and 42 can be rendered conductive.

As soon as the electrodes 12, 14 and 16 are actuated to a position where a circuit is completed through the electrodes in conjunction with the metal charge 18, maximum current flows through the electrode 14 and a direct-current voltage proportional to the current is imposed across each of the control resistors 272 and 296, with the result that the differential of the direct-current voltages across resistors 270-272 and 294-296 is such as to place a less negative bias on the grid of valve 184 and a more negative bias on the grid of valve 186.

The less negative or more positive bias on the grid 220 of valve 184 renders the control valve 184 more conducting so that more current flows through the circuit extending from the negative terminal of the supply rectifier bridge 232 through the reactor 250, conductor 248, segments 210 and 200 of controllers 190 and 188, respectively, conductor 246, potentiometer resistor 164, conductors 70, 74 and 76, resistors 78 and 102, conductor 104, a part of resistor 244, the flexible lead or conductor 242, self-biasing resistor 240, cathode 224, and anode 216 of the control valve 184, and conductor 228 to the positive terminal of the supply rectifier bridge 232. The current flowing through that part of potentiometer resistor 164 in the grid-cathode circuit of valves 36 and 38 renders the direct-current biasing potential on the grids 112 and 114, respectively, more negative to block the firing of the valves 36 and 38 and prevent the flow of current therethrough to the motor 26.

At the same time that the valve 184 becomes conducting, the change in the biasing potential on the grid 222 of control valve 186 is such as to decrease the current passed by the valve 186, with the result that the current flow through the potentiometer resistor 166 is so decreased or becomes zero that the direct-current biasing potential on the grids 116 and 118 of valves 40 and 42, respectively, becomes less negative or

more positive, and the valves 40 and 42 become conducting to pass current to the motor 26. The motor circuit thus established extends from the center tap of the transformer 54 through conductor 110, contact member 106 of contactor 102, conductor 104, resistor 102, armature windings 32 of the motor 26, resistor 100, conductors 98 and 96, the parallel conductors 90 and 94—92, cathodes 64 and 66, respectively, and anodes 48 and 50, respectively, of the valves 40 and 42, respectively, to the terminals of the secondary winding of the transformer 54 to so energize the motor 26 as to effect an operation thereof in a direction to raise the electrode 14.

The electrode 14 is thus raised to a position for ideal operation of the arc furnace in which position the direct-current voltage across each of control resistors 270 and 294, which is proportional to the arc potential, and the direct-current voltage across each of control resistors 272 and 296 and which is proportional to the current flowing through the electrode 14, are balanced, and a zero differential appears across the series connected resistors 270—272 and the series connected resistors 294—296. Under such conditions, the self-biasing resistors 240 and 252 function to maintain sufficient bias on the grids of control valves 184 and 186, respectively, whereby they are sufficiently conducting to pass current through potentiometer resistors 164 and 166, respectively, that the direct-current biasing potential on the grids of valves 36—38 and 40—42, respectively, is sufficient to block the valves from passing current to the motor 26.

If the ideal operating condition for the arc furnace 10 is changed in any manner whatsoever, the balance of the direct-current voltages across control resistors 270—272 and 294—296 is upset with the result that the bias on the grids of control valves 184 and 186 is changed to effect an operation of the motor 26 in a predetermined manner to again establish the required balance between the current and the potential across the arc.

If, for example, the electrode 14 should come in contact with the metal charge 18 as by reason of the cave-in of the metal, the arc potential is reduced to a minimum, and the current flowing through the electrode 14 is a maximum with the result that the differential of the direct-current voltages across control resistors 270 and 272 is of such a polarity as to render the grid of control valve 184 more positive and thereby render the valve 184 more conductive. As described hereinbefore, when the valve 184 is thus rendered more conducting, the flow of current through the potentiometer resistor 164 so changes the grid-cathode potential of valves 36 and 38 as to render them non-conducting.

At the same time, the differential of the control voltages across resistors 294 and 296 is such as to place a more negative bias on the grid 222 of control valve 186 to decrease the current flow through the control valve 186. Under such conditions, the direct-current biasing potential on the valves 40 and 42 is such that the valves are rendered less negative, and current flows therethrough to the motor 26 to cause its operation to raise the electrode 14.

During the foregoing described operations of the system, it is to be noted that the winding 318 of the switching contactor 192 is energized in accordance with the current flow through the electrode 14, and is thus energized in accordance with a component of the direct-current voltages

controlling the bias of the control valve 184. At the same time, the winding 316 of the switching contactor 192 is connected by reason of the "break" contact members 306 and 312 across part of the resistor 256, which, in turn, is connected across the terminals of the armature windings of the motor 26 whereby the winding 316 is energized in accordance with the terminal potential of the motor 26. As connected, the polarity of the voltage impressed across the winding 316 when the motor is operating to effect a lowering of the electrode 14 is the same as that impressed across the winding 318. If the motor is operating to effect a raising of the electrode 14, then the polarity of the voltage impressed across the winding 316 opposes the polarity of the voltage impressed across the winding 318. The physical characteristics of the switching contactor 192 are such that in order to actuate the make contact members 314, 310 and 308 to a circuit closing position, the polarities of the voltage impressed across the windings 316 and 318 must be identical, and the winding 316 must be energized a predetermined amount depending upon a predetermined current flow through the motor armature 32.

If during the operation of the system as described hereinbefore, the control valve 184 should fail, the failure of the control valve 184 would normally interrupt the flow of current through the potentiometer resistor 164, with the result that the bias on the grids 112 and 114 of the valves 36 and 38, respectively, becomes more positive to pass current to the motor 26. Unless such current is controlled, the motor 26 would be operated to drive the electrode 14 through the furnace or the current flow might cause serious damage to the electric valves connected in the system.

As soon as the valve 184 fails, the flow of current from the valves 36 and 38 through the motor 26 is so increased that the potential drop across the resistor 256 becomes so large that the winding 316 is energized to cooperate with the winding 318 to actuate the "make" contact members 308, 310 and 314 to circuit closing positions and to immediately thereafter actuate the "break" contact members 306 and 312 to circuit opening positions.

The contact member 314 shunts the control valve 184 from the circuit with the potentiometer resistor 164, whereas contact members 310 and 308 establish a holding circuit for the switching mechanism 192. The holding circuit extends from the negative side of the supply rectifier bridge 232 through reactor 250, conductor 248, segments 210 and 209 of the controllers 190 and 188, respectively, conductors 246 and 330, contact member 310, conductor 322, energizing winding 316, contact member 308, resistor 328, and conductors 324 and 228 to the positive side of the rectifier bridge 232. This holding circuit maintains the contact member 314 of the contactor 192 in circuit closing position to establish a supply circuit for the potentiometer resistor 164 which extends from the negative terminal of the supply rectifier bridge 232 through the reactor 250, conductor 248, segments 210 and 200 of controllers 190 and 188, respectively, conductor 246, potentiometer resistor 164, conductors 78, 74 and 76, resistors 78 and 102, conductor 104, a part of resistor 244, flexible lead or conductor 242, resistor 326, contact member 314, and conductors 324 and 228 to the positive terminal of the supply rectifier bridge 232. The

flow of current through the circuit thus established places a large negative bias on the grids of the valves 36 and 38 to insure that the valves 36 and 38 will not pass current to the motor 26. While the valve 184 is thus shunted, a new valve 5 may be replaced for the valve which failed.

After the replacement of the control valve 184, the system may be placed on automatic operation again by operating the single phase controller 190 to the "lower" position in which position segments 204 and 206 interrupt the circuits from the control resistors 294-296 and 270-272, respectively, the segment 212 interrupts the circuit to the energizing winding of contactor 108 to interrupt the supply circuit to the motor 26 from the valves 40 and 42, and the segment 210 interrupts the circuit from the supply rectifier bridge 232 through the potentiometer resistor 164, whereby the grids of the valves 36 and 38 become positively biased, and the valves 36, 38 conduct current to the motor 26 in the manner hereinbefore described to effect a lowering of the electrode 14. At the same time the segment 210 interrupts the energizing circuit for the winding 316 to deenergize the winding 316 whereby the "make" contact members 314, 310 and 308 are actuated to a circuit opening position, and the "break" contact members 312, 306 are actuated to their circuit closing positions to again connect winding 316 to be energized in accordance with the terminal potential of the motor 26 and to again connect the control valve 184 in circuit where the valve 184 is disposed to control the bias on the valves 36 and 38.

As soon as the control valve 184 is again connected in circuit relation with the potentiometer resistor 164, the single phase controller 190 is returned to the "off" position to connect the control resistor 270-272 and 294-296 in circuit relation with the control valves 184 and 186, respectively, to control the operation of the control valves, and at the same time the contactor 108 is connected in circuit to actuate the contact member 106 to the circuit closing position to connect the motor 26 to be supplied from the valves 40 and 42 when the operating conditions of the system so demand.

It will, of course, be appreciated that manual control to raise the electrode 14 can be obtained through operation of the master controller 188 to simultaneously effect the raising of the electrodes 12, 14 and 16 or by a manual operation of the single phase controller 190 to raise the electrode 14 independently of the electrodes 12 and 16. For example, the controller 190 may be actuated to the "raise" position, in which position the segment 214 interrupts the energizing circuit for the contactor 86 to interrupt the supply circuit from the valves 36 and 38 to the motor 26. At the same time, the segments 204 and 206 interrupt the supply circuit from the control resistors 294-296 and 270-272, respectively, and segment 208 interrupts the circuit from the supply rectifier bridge 234 to the potentiometer resistor 166 whereby the valves 40 and 42 are rendered highly conducting to pass current to the motor 26 to effect an operation thereof to raise the electrode 14.

With the system of this invention it is apparent that the control system is protected where the control valve normally controlling the operation to lower an electrode fails making it impossible to damage the furnace and control apparatus associated therewith by reason of such failure of

the control valve. The protection thus afforded by the system of this invention is instantaneous and automatic and can be obtained in other control circuits by the addition of standard parts without greatly increasing the cost of the equipment.

I claim as my invention:

1. In a control system, in combination, a reversible motor the operation of which is to be controlled, a pair of valve means disposed to selectively connect the motor to a source of alternating current to control the direction of operation of the motor, each pair of valve means having a grid control circuit including a resistor for controlling the conductivity thereof, a control means disposed to be operated for selectively controlling the flow of current through the resistors for rendering the pair of valve means selectively conductive, each of the resistors being so connected that when current does not flow therethrough the associated valve means is rendered conducting, a source of control voltage responsive to the operation of the motor for effecting an operation of the control means, and switching means disposed for operation in response to a predetermined operation of the motor for rendering the control means inoperative with respect to one of the pair of valve means and to effect a flow of current through the resistor in the grid circuit of said one of the pair of valve means to render said one of the pair of valve means non-conductive.

2. In a control system, in combination, a reversible motor the operation of which is to be controlled, a pair of valve means disposed to selectively connect the motor to a source of alternating current to control the direction of operation of the motor, each pair of valve means having a grid control circuit including a resistor for controlling the conductivity thereof, control means disposed to be operated for selectively controlling the flow of current through the resistors for rendering the pair of valve means selectively conductive, each of the resistors being so connected that when current does not flow therethrough the associated valve means is rendered conducting, a source of control voltage responsive to the operation of the motor for effecting an operation of the control means, and a switching mechanism disposed to be actuated to a switching position in response to a predetermined operation of the motor and to a component of the source of control voltage to render the control means inoperative with respect to one of the pair of valve means and to effect a flow of current through the resistor in the grid circuit of said one of the pair of valve means to render said one of the pair of valve means non-conductive.

3. In a control system, in combination, a reversible motor the operation of which is to be controlled, a pair of valve means disposed to selectively connect the motor to a source of alternating current to control the direction of operation of the motor, a control means disposed to be operated for rendering the pair of valve means selectively conductive, a source of control voltage responsive to the operation of the motor for effecting an operation of the control means, and a switching mechanism disposed to be actuated to a switching position to render the control means inoperative with respect to one of the valve means and to render said one of the valve means non-conductive, the switching mechanism having a pair of windings disposed to be energized, one of the windings being disposed to be

energized in response to the operation of the motor and the other of the windings being disposed to be energized in response to a component of the source of control voltage whereby the windings cooperate under predetermined operating conditions of the motor to effect the actuation of the switching mechanism.

4. In a control system, in combination, a reversible motor the operation of which is to be controlled, a pair of valve means disposed to selectively connect the motor to a source of alternating current to control the direction of operation of the motor, a control means disposed to be operated for rendering the pair of valve means selectively conductive, a source of control voltage responsive to the operation of the motor for effecting an operation of the control means, a switching mechanism disposed to be actuated to a switching position to render the control means inoperative with respect to one of the valve means and to render said one of the valve means non-conductive, the switching mechanism having a pair of windings disposed to be energized, one of the windings being disposed to be energized in response to the operation of the motor and the other of the windings being disposed to be energized in response to a component of the source of control voltage whereby the windings cooperate under predetermined operating conditions of the motor to effect the actuation of the switching mechanism, and means connected in circuit relation with said one of the windings disposed to be operated to effect the deenergization of said one of the windings.

5. In a control system, in combination, a reversible motor the operation of which is to be controlled, a plurality of pairs of electric valves disposed to selectively connect the motor to a source of alternating current to control the direction of operation of the motor, the electric valves having grids to be utilized for controlling the conductivity thereof, a grid control circuit including a resistor for each pair of the electric valves, a discharge valve having a control grid therein to be utilized for controlling the bias of the grids of the pair of electric valves associated therewith, a pair of control voltages variable in opposite senses in response to the operation of the motor for impressing predetermined biases on the grids of the discharge valves, and a switching mechanism disposed to be actuated to a switching position in response to a predetermined operation of the motor in one direction and to a component of one of the control voltages to render one of the discharge valves inoperative and simultaneously therewith render the pair of electric valves associated with said one of the discharge valves non-conducting to prevent further operation of the motor in the one direction.

6. In a control system, in combination, a reversible motor the operation of which is to be controlled, a plurality of pairs of electric valves disposed to selectively connect the motor to a source of alternating current to control the direction of operation of the motor, the electric valves having

grids to be utilized for controlling the conductivity thereof, a grid control circuit including a resistor for each pair of the electric valves, a discharge valve having a control grid therein to be utilized for controlling the bias of the grids of the pair of electric valves associated therewith, a pair of control voltages variable in opposite senses in response to the operation of the motor for impressing predetermined biases on the grids of the discharge valves, and a switching mechanism disposed to be actuated to a switching position to render one of the discharge valves inoperative and simultaneously therewith render the pair of electric valves associated with said one of the discharge valves non-conducting, the switching mechanism having a pair of windings disposed to be energized, one of the windings being disposed to be energized in response to the operation of the motor and the other of the windings being disposed to be energized in response to a component of one of the control voltages whereby the windings cooperate under predetermined operating conditions of the motor in one direction to effect the actuation of the switching mechanism.

7. In a control system, in combination, a reversible motor the operation of which is to be controlled, a plurality of pairs of electric valves disposed to selectively connect the motor to a source of alternating current to control the direction of operation of the motor, the electric valves having grids to be utilized for controlling the conductivity thereof, a grid control circuit including a resistor for each pair of the electric valves, a discharge valve having a control grid therein to be utilized for controlling the bias of the grids of the pair of electric valves associated therewith, a pair of control voltages variable in opposite senses in response to the operation of the motor for impressing predetermined biases on the grids of the discharge valves, a resistor connected across the motor to provide a source of potential proportional to the terminal potential of the motor and having a polarity depending upon the direction of operation of the motor, and a switching mechanism disposed to be actuated to a switching position in response to a predetermined potential across said resistor source as the motor operates in one direction and to a component of one of the control voltages to render one of the discharge valves inoperative and simultaneously therewith render the pair of electric valves associated with said one of the discharge valves non-conducting to prevent further operation of the motor in the one direction.
